REFERENCE DEVICE

Hazel Terry, Valparaiso, Ind.

Application August 8, 1938, Serial No. 223,661

1 Claim. (Cl. 312—155)

My invention relates to improvements in reference devices and it includes the special features pointed out in the claim.

The purpose of my invention is to provide a handy reference device that is especially adapted for kitchen use, in the shape of a kitchen library; that provides an open cabinet, in which a plurality of open edged containers are secured; that makes the assembly equally available whether the cabinet is supported on a wall fastening or it rests on a table; and that each container is definitely allocated to a specific branch of the culinary art, and the storage therein of separate cards bearing recipes related to the same subject, such for instance, as meats, vegetables, baking, canning, preserving, etc., etc., or subdivisions of such subjects or any other designations imprinted on the facing edge of the containers.

With these ends in view I illustrate in the accompanying drawing such instances of adaptation as will disclose the outstanding features of the invention without limiting myself to the specific details shown thereon and described herein.

Fig. 1 is a front view of my kitchen library.

Fig. 2 is an end elevation of Fig. 1.

Fig. 3 is a diagrammatic end elevation of a cabinet attached to the wall.

Fig. 4 is a similar view to Fig. 3 showing the cabinet resting on a table.

Fig. 5 is an enlarged end elevation of the hinging of the containers.

Fig. 6 is a semi-perspective of a detached container.

In the use of my kitchen library which I have chosen to name "Chef-an-ette" I may adapt the invention to whatever changes of equivalents and alternatives of structure that the exigencies of varying conditions and phases of adaptations may demand without departing from the broad underlying scope of the invention.

A cabinet formed of metal or otherwise, has a back 1, ends 2, and a base 3. The back may have an opening 4 so that it is readily supported on a wall. The base 3 projects forward in advance of the front edge of the containers 5 where it may have a rolled or other edge 6, against which the front of the container rests when the cabinet is positioned against a wall.

The containers 5 on the front edge 1 are provided with a loop 8 or a bearing that serves as a pivot on the rod 9. This rod is attached to the ends 2 of the cabinet. At the right hand end it may have a hook 10 on which bills etc., may be hung. To support the weight of a single one or more of the containers as they are swung forward

as shown in Fig. 2 a fastening screw 11 passing through the opening 4 may be used.

The rod 9 may be removable from the cabinet so that the containers may be detached for cleaning the base 3. By reason of the base not having a front projection to hold the containers in place no obstruction is present, hence, the base may be easily wiped off or washed.

The cabinet may be enameled by baking etc., and the containers may be formed of Bakelite, Pyralin, Catalin or any other plastic, or of any other material. The front of each one will contain on the front edge 7 the name of the subject that is appropriate to the character of the contents. For specific kitchen or similar use the containers may hold cards 12. The faces 13 of the containers may be cut away at 14 to make the cards more easily accessible. These containers are closed at the top 15 and the bottom 16 and are left open on the rear side 17.

In the practice of my invention it is important that each container rests with its closed lower edge 16 flatly against the bottom 3 of the cabinet, that the bearings 8 are above the bottom 3; that the front edge of the bottom 3 projects forward of the front edge 7 of the containers; that the rod 9 is in line with the edge 7; and that the containers are positioned entirely between the rod 9 and the back 1 of the cabinet.

Figs. 3 and 4 clearly show how accessible the contents of the container are by reason of the open edge 17 being uppermost as the container is tilted forward. The ends 2 of the cabinet extend forward from the position of the rod 9 at 18 to serve as a bracket to support the rolled front edge 6.

The ends 2 where the rod 9 passes through may be reinforced in any desired manner and the left hand end may have any kind of spring or other catch to hold the rod in place, or the rod may be threaded at its outer end and a nut 19 used to hold it in the cabinet, the hook end 10 serves to hold the rod against endwise movement toward the left side.

In the use of my cabinet the equivalent structure of Fig. 3 or Fig. 4 may be followed, either form being equally serviceable whether the cabinet is hung on a wall or if it rests on a table. In either case the containers 5 are in a closed position when not in use so that their bottom edges 16 rest by gravity on the base or bottom 3 of the cabinet while their rear sides 17 are adjacent the back 1 and they are all held pivotally on a rod that is common to all the containers.

In any case whether the cabinet is used on a

table or on a wall the containers are assembled as a unit against misplacement. When the contents of any container are to be inspected it is swung on its pivot located adjacent the front edge 7. This pivot is in spaced apart relation to the bottom edge 16.

In swinging the containers forward to make their contents accessible they remain assembled on the pivoting rod, that is supported in the ends 10 2 and is positioned above the base 3 and to the rear of the front edge 6. The front edge 7 of a container will rest on the front edge 6 of the bottom of the cabinet when the container is swung forward while the cabinet is hanging on a wall. 15 Should the cabinet be placed on a table the front edge 7 of the container, in its open position will also rest on the table. Whether the cabinet is on a wall or table, the open edge 17 of a container faces upward and slopes forward and

downward at an angle to the horizontal so that the entire swing is greater than 100 degrees from the closed to the open position.

What I claim is:

A reference utility cabinet comprising a bottom and a back wall joined by end members to provide a compartment open at its top and front, a rod secured to the end members and spaced upwardly and inwardly from the front edge of said bottom, a plurality of rectangular containers, each having side, top, front and bottom walls and an open rear side, said containers being provided with means pivotally securing them above their bottom walls upon said rod, whereby they may rest by gravity upon the bottom with their open sides adjacent the back wall or be swung to a position in which they rest against the front edge of said bottom. 10 15

HAZEL TERRY.
